UNITED STATES PATENT OFFICE.

WILLARD A. PETTEYS, OF WILCOX, NEBRASKA.

GRAIN CLEANER, SEPARATOR, AND DRIER.

1,398,275.

Specification of Letters Patent. Patented Nov. 29, 1921.

Application filed June 4, 1918. Serial No. 238,155.

To all whom it may concern:

Be it known that I, WILLARD A. PETTEYS, a citizen of the United States, residing at Wilcox, in the county of Kearney, State of Nebraska, have invented a new and useful 5 Grain Cleaner, Separator, and Drier; and I do hereby declare the following to be a full, clear, and exact description of the invention, such as will enable others skilled in the art 10 to which it appertains to make and use the same.

This invention relates to an improved machine for screening, separating and drying grain, as wheat and corn and other grains 15 and one of the objects of the invention is to provide a machine of this kind especially adapted for use in connection with grain elevators.

A further object of the invention is to provide a trough member provided with a plurality of screens of different mesh, each being inclined relative to the trough, and arranged in tiers, the screens of one tier being of different mesh than the screens of the adjacent 25 tier, and overlapping each other.

A further object of the invention is to provide a machine of this kind having a plurality of shutters, one series near the lower end of the trough, the other near the upper 30 end of the trough, said shutters adapted to perform the function of controlling the force and the amount of air to be permitted to circulate through the grain during the screening and separating process and also to 35 catch and convey the dockage that drops through the screens into a receptacle at the lower end of the trough.

A further object of the invention is the provision of means for supporting the 40 screening trough, whereby the inclination of the trough may be varied for facilitating the screening, separating and drying of the grain.

In practical fields the details of construction may necessitate alterations falling 45 within the scope of what is claimed.

The invention comprises further features and combination of parts as hereinafter set forth shown in the drawings and claimed.

50 In the drawings:—

Figure 1 is a view in side elevation of the improved screening and separating machine constructed in accordance with the invention.

Fig. 2 is a plan view.

55 Fig. 3 is a sectional view on line 3—3 of Fig. 2.

Fig. 4 is a sectional view on line 4—4 of Fig. 1.

Fig. 5 is an enlarged, fragmentary, sectional view of the discharge end of the 60 trough or chute.

Referring more especially to the drawings, 1 designates an elongated trough shaped chute or member comprising the sides 2 and 3. The upper portions of the sides 2 and 3 65 are connected and braced by transverse channel bars 4, through which the bolts 5 extend. On the outer faces of the sides are vertical reinforcing bars 6, through which the bolts 5 also extend, said bolts having nuts, for 70 drawing the parts together and reinforcing the sides of the trough shaped chute. These bars have additional securing means such as screws 7. Secured to the inner faces of the sides are a series of opposed angle bars, 8, 9, 75 10, 11, 12 and 13, 14, 15 and 16, which are arranged in stepped relation and overlying each other, thereby providing guides for two series of screen members, designated 17 and 18. These screen members consist of upper 80 and lower frames, which are rectangular, and provided with wire fabric material 19 or perforated metal which is secured to said frames in any suitable manner. The mesh of the wire fabric of the members 17 is 85 larger than the mesh of the wire or metal fabric of the members 18, which may be removed, for the purpose of screening corn and the like. In fact by providing the upper and lower screens with finer and coarser 90 mesh, grain may be separated according to various sizes. The angle bars are inclined with relation to the trough shaped chute, in order to hold the screen members inclined as shown. By disposing the trough shaped 95 member on an inclination and owing to the stepped relation of the screen members, the grain may pass from one screen member to the other. The screen members may be removed from their guides (in which they are 100 frictionally held) by sliding the screening members in the directions of the arrow α .

The angle bars forming the guides for the screening members are secured to the inner faces of the sides of the trough shaped chute 105 by means of screws or the like 20. However, through certain of said angle bars rod bolts 21 extend. Surrounding the rod bolts 21 are sleeves 22 which are interposed between certain opposite angle bars. Pivoted 110 upon the bolts 21 at the opposite ends of the trough shaped chute are bail shaped mem-

bers 23, which are provided with eyes 24, in which are secured the ends of ropes or cables 25. By means of these ropes or cables 25 and 26 the trough shaped chute or screening machine may be supported on any desired inclination from a grain elevator (not shown) to any one of a plurality of bins (not shown), so that various grains when dumped into the hopper 27 may pass through a screening process during the passage to the bins. The cable or rope 25, as well as the rope or cable 26 may be adjusted, to alter the inclination of the screening machine or trough shaped chute. Suitable open frames 28 are hinged at 29 to the side 3 of the chute. These frames 28 are interposed between the channel bars 4, there being flanges 30 on the channel bars to support the frames 28 when closed. These frames 28 are covered by pieces of wire fabric or mesh work 31, to prevent the grain when passing from one screening member 17 to the next screening member 17, from bounding out of the trough shaped chute. Mounted in suitable bearings 32 adjacent the lower edges of the sides 2 and 3 of the chute are rocking shafts 33 arranged in series, the upper series being greater than the lower. These transverse rocking shafts 33 are held in their bearings 32 by the longitudinal strips 34, which are secured to the lower edges of the sides 2 and 3 by means of suitable screws 35. The shafts 33 are provided with shutters 36 which are arranged to overlap each other as shown in Fig. 3.

The shafts 33 adjacent one of the sides of the chute are provided with right angle extending arms 38 and 39. The arms 38 of the lower series of shafts have pivoted thereto a connecting bar 40. A connecting bar 41 is pivoted to the ends of the arms 39 of the upper series of shafts. Certain of the arms 38 and 39 respectively are extended to provide levers 42 and 43, which have handles 44. Segment racks 45 are secured on the outer face of the side 2 of the trough shaped chute, whereby the teeth of which may be engaged by the ribs 46 of said levers, to hold the levers in different adjusted positions. It is to be observed that the lower series of shutters may be opened independently of the upper series and vice versa. By opening both series of shutters a current of air is allowed to pass through the chute throughout its entire length, and it is apparent that upon opening either one of the series of shutters, a current of air is allowed to pass through only a portion of the chute. In the operation the machine is tilted, substantially on a forty five degree inclination whereby its hopper end will become positioned under an elevator spout (not shown) of an elevator drive way, and the lower end may be disposed to discharge or dump into a suitable bin (not shown). Such a bin may comprise compart-

ments to receive the different sized grain being sorted and also the dockage. Upon opening the spout, the grain passes through the hopper to the upper screen, and striking the upper screen rebounds to the top or hinged screen frame and then rolls over and along the first screen until it again falls on the first screen and again rebounds. This process continues until the grain drops or empties into the bin or dump. During this process the current of air rushes through the screen either from the front or behind, drying the grain as it passes through the chute, and also blows the chaff and dust, dirt and like from the same. The pounding and rubbing that the grain is subjected to as it rushes through the machine, at the same time the air cleans, scours and dries it assists in removing the chaff or other particles from the grain. The chaff is forced out and the weed seed and shrunken kernels, usually called dockage are separated. This dockage is worthless and when retained at the elevator establishment the freight is saved which has been heretofore paid on shipping the same, and the dockage so retained may be sold as screenings. The grain thus cleaned raised the grade of the grain, and consequently commands higher price. Gravitation draws the grain through the machine and if greater or less speed in the screening of the grain is required either end of the machine may be raised or lowered. One of the shutters 36 such as indicated at *a* may be removed, for leaving a space. This space when the shutter as indicated at *a* is removed allows the dockage to pass therethrough into a receptacle (not shown). This space will also permit a current of air to pass through the chute for cleaning the grain. However, when this space is closed by the shutter as indicated at *a* the grain or the like is conveyed to the lower end of the chute, for discharging into a second receptacle.

The invention having been set forth what is claimed as new and useful is:—

1. In a grain separating structure comprising a trough shaped rectangular chute, upper and lower spaced series of screening members, each of said screening members having upper and lower parallel inclined guides secured to the inner sides of the chute, screening frames of different mesh supported by the said guides, an upper and lower independent series of hinged shutters constituting a flooring for the chute and baffle plates for the upper and lower series of screening members, and independent means to selectively open either series of shutters to regulate the air draft within the chute. 115

2. A grain separating structure comprising a rectangular trough, upper and lower spaced screening members in said trough, each of said screening members having inclined, overlapping guides fixed to the inner 130

sides of said trough, frames provided with wire mesh of different size supported by said guides, an upper and lower series of independently hinged shutters constituting a 5 flooring for the chute and baffle plates for the upper and lower series of screening members, transverse rock shafts for selectively operating and angling either series of said shutters to regulate the air draft within the 10 upper or lower portion of the chute, segmental racks and vertical arms extending from said rock shaft for engagement with said rack whereby the said shutters may be maintained in their predetermined position.

15 3. A grain separating structure comprising a chute, upper and lower spaced screening members within said chute, hinged open frames above said screening members, each of said screening members having overlapping, parallel inclined guides secured to the 20 inner sides of said chute, wire frames of different mesh supported by said guides, an

upper and lower series of independently hinged shutters constituting a flooring for the chute and baffle plates for the upper and 25 lower series of screening members, rock shafts for selectively operating and angling either series of said shutters to a predetermined degree to regulate the air draft within the upper or lower portion of the chute, 30 segmental racks on one side of said trough, vertical arms extending from said rock shaft for engagement with said racks whereby the shutters may be maintained in their angular set position and flexible means for supporting the ends of the chute in its inclined, 35 operative position.

In testimony whereof I have signed my name to this specification in the presence of two subscribing witnesses.
